DESOLDERING TOOL

Alvis R. Knowles, Torrance, Calif., assignor to Eldon Industries, Inc., Hawthorne, Calif., a corporation of California

Filed Oct. 9, 1968, Ser. No. 13,894

Term of patent 14 years

Int. Cl. D8—02

U.S. Cl. D8—30

FIG. 1.

FIG. 2.

FIG. 3.

FIG. 4.

FIG. 5.

FIG. 6.

FIG. 1 is a top elevational view of the desoldering tool embodying the design of my invention;

FIG. 2 is a side elevational view thereof, taken from the right side of FIG. 1;

FIG. 3 is a bottom elevational view thereof;

FIG. 4 is a side elevational view thereof, taken from the left side of FIG. 1;

FIG. 5 is a front elevational view thereof;

FIG. 6 is a rear elevational view thereof.

I claim:

The ornamental design for a desoldering tool, substantially as shown and described.
